[57] CLAIM

The ornamental design for a set of supplemental reflectors for motorcycle and rider's helmet, as shown and described.

DESCRIPTION

FIG. 1 is a front elevational view of a set of supplemental reflectors for motorcycle and rider's helmet showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a perspective view thereof; on an enlarged scale; and

FIG. 7 is a top plan view thereof on an enlarged scale. The motorcycle and rider are shown in broken lines for illustrative purposes only.

Fig. 5
